UNITED STATES PATENT OFFICE.

FRANK FOSTER, OF PRESTON, ENGLAND.

INKING MECHANISM FOR PRINTING PRESSES.

Application filed February 6, 1923. Serial No. 617,386.

To all whom it may concern:

Be it known that I, FRANK FOSTER, a subject of the King of Great Britain, residing in Preston, England, have invented certain new and useful Improvements in or Relating to Inking Mechanism for Printing Presses (for which I have filed an application in Great Britain Jan. 16, 1922, Serial No. 1,372), of which the following is a specification.

This invention relates to inking mechanism for printing presses of the kind comprising an ink fountain containing a rotating roller for delivering the ink to the ink drum or the like, and adjustable knife, scraper blade, or the like being arranged adjacent to said roller to regulate the amount of ink delivered.

To obtain uniform and effective printing, particularly in the case of large newspaper machines in which ink has to be supplied to a series of columns, it is essential that means should be provided for accurately adjusting the position of the knife in relation to the fountain roller at various points, so that uniform inking of the whole series of columns is produced.

Various methods have been suggested for this purpose.

In one method it has been proposed to provide the fountain with a platform on which a series of screws are mounted so as to press on the knife at desired points, each screw being fitted with a worm wheel adapted to be turned from the ends of the fountain by means of a worm carried on an adjusting rod to regulate the pressure of the screw on the knife, thus regulating the amount of ink delivered by the fountain roller. In this arrangement, the screws have been located two to each column, and the ends of the adjusting rods have been numbered to correspond with said columns.

In another method a series of cam actuated sliding plungers, which may be spring pressed, have been arranged to bear on the knife, the cams being actuated by flexible transmission wires on the Bowden system from a point outside the duct, to vary the pressure on the plungers.

The present invention has for its object to provide improved means for adjusting the knife at the desired points, from the outside of the fountain.

To this end, according to the invention, pressure is applied to the knife at the de-

sired points by means of a series of slidably mounted plungers operated by cams or levers. The cams or levers are carried on cross shafts rotated by suitable mechanism operable from the outer ends of the ink fountain, such as rotatable rods for example, the arrangement being such that each cam or lever may be separately operated and held in any desired position.

Each plunger is spring supported and may be formed with a flat head and a collar or other abutment for one end of a coiled spring arranged within the socket in which the plunger is mounted.

In machines for printing newspaper, a pair of plungers may be arranged to operate on the knife at points corresponding to each column to be inked and all the rods for operating the cross shafts may be arranged to be operable from one end of the fountain or they may be divided into two groups, operable one from each end of the fountain. The said rods may be arranged in banks and suitably numbered, to indicate the columns or the like, to which they refer.

The invention is applicable to fountains of the undershot and overshot type and to printing machines of various kinds.

To enable the invention to be fully understood it will now be described by reference to the accompanying drawings in which:

Fig. 1 is a front elevation of an end portion of an apparatus constructed according to the invention and adapted to be applied to an ink fountain.

Fig. 2 is an end view, and

Fig. 3 is a plan view of same.

Fig. 4 is an end view shewing the apparatus applied to a fountain of the overshot type and

Fig. 5 is a plan view thereof.

Fig. 6 is an end view shewing the apparatus applied to a fountain of the undershot type, and

Fig. 7 is a plan view thereof as seen from below.

As shewn in Figs. 1 to 3 the apparatus comprises a bridge piece 1, in the form of an open frame adapted to be secured on an ink fountain, the knife being indicated at 2, pressure is applied to the knife 2 by means of a series of plungers 3 (one only being shewn), slidably mounted in sockets 4, each plunger having an enlarged head portion 5 forming an abutment for one end of a coil spring 6. Each plunger is

adapted to be pressed against the knife by means of a cam or lever 7 (one only being shewn) bearing on the plunger head and rigidly secured on a cross shaft 8 rotatably mounted in the bridge piece. The shaft 8 also carries a lever 9, rigid therewith and having a collar portion 10 containing a circular block 11. An adjusting rod 12 rotatably mounted in one end of the apparatus and extending longitudinally of same is formed with a screw threaded portion 13 which passes freely through openings 14 formed in the collar 10 and engages a screw threaded hole bored in the block 15 11.

The openings 14 are cut away as shewn at 15 in Fig. 1 and the outer end of the rod 12 is squared, so that it may be rotated by means of a key or spanner.

20 It will be understood that the collar 10 is free to turn on the block 11.

With the above described construction, when the apparatus is in position on an ink fountain, as shewn in Fig. 4, on turning the rod 12, the shaft 8 will also be rotated, raising or lowering the cam or lever 7 according to the direction of rotation of rod 12 and thus regulating the pressure of the plunger 3 on the knife 2 and consequently, the delivery of the ink at that point.

35 The plungers 3 may be provided at any desired points, one or more to each column and the ends of the rods 12 may be arranged in banks on the end of the bridge and numbered in the known manner.

40 All the plungers may be operated from the same end of the bridge as shewn or the series may be divided and some operated from one end and the remainder from the other, as will be readily understood.

45 Figs. 4 and 5 shew the apparatus applied to a fountain 16 of the overshot type, the ink roller being indicated at 17, the plungers all being operated from the same end of the apparatus.

50 Figs. 6 and 7 shew the apparatus applied to a fountain 18 of the undershot type, the inking roller being indicated at 19 and the knife at 20. In this case also, all the plungers are operated from the same end of the bridge.

55 By means of this invention, since the springs under the plungers are always under compression, backlash is entirely

eliminated and so very fine adjustments of pressure may be produced on all desired points of the knife.

The spring plungers may be operated by mechanism other than that illustrated and coming within the scope of the appended claims.

Having thus described the nature of the said invention and the best means I know of carrying the same into practical effect, I claim:—

1. Inking mechanism for printing presses comprising in combination, an ink trough, a roller therein, a blade mounted longitudinally of the roller, a bridge piece, a plurality of slideable plungers mounted on the bridge piece and engaging the blade, mounted on the bridge piece, a plurality of transverse shafts mounted in the bridge piece, actuating members on the transverse shafts 70 engaging the plungers, a lever on each transverse shaft, operating rods for moving the levers extending longitudinally of the bridge piece, and springs tending to move the plungers out of engagement with said 80 blade.

2. Inking mechanism for printing presses, comprising an ink trough, a roller in said trough, a blade mounted longitudinally of said roller, a bridge piece associated with said trough, a plurality of shafts mounted transversely of said bridge piece, a plurality of plungers slidably mounted in said bridge piece and engaging said blade, spring means tending to move said 90 plungers out of engagement with said blade, an actuating member carried by each of said transverse shafts engaging one of said plungers, a lever fixed to each of said transverse shafts, a collar carried by each of said levers, each of said collars having a pair of diametrically disposed openings, a circular block mounted in each of said collars, each of said blocks having a diametrical screw-threaded passage, and an operating rod for each of said plungers 100 extending longitudinally of said bridge piece and having a screw-threaded end extending through the openings in one of said collars and engaging the screw-threads of 105 the block carried thereby.

In testimony whereof I have signed my name to this specification.

FRANK FOSTER.
